UNITED STATES PATENT OFFICE.

WILLIAM H. FULLINGTON, OF CLEVELAND, OHIO.

SPREADER.

Application filed August 22, 1921. Serial No. 494,271.

To all whom it may concern.

Be it known that I, WILLIAM H. FULLINGTON, a citizen of the United States, residing at Cleveland, in the county of 5 Cuyahoga and State of Ohio, have invented certain new and useful Improvements in Spreaders, of which the following is a specification.

In making rope it is customary to guide 10 the strands to the rope being formed, by means of what is known as a spreader, the strands being revolved by suitable devices, carrying the spreader therewith.

The object of the present invention is to 15 provide an improved spreader for use in this connection, which will effectively hold the strands apart until sufficient twist has been made in the rope, the spreader consisting of a body which is provided with 20 notches in its edge through which the strands are guided.

The present spreader also embodies two members which are spaced apart, one being of smaller diameter than the other so 25 that the strands are guided toward the formed rope at an inclination or angle to give the desired pitch to the twist. Further details of the invention will be apparent from the following description.

30 In the accompanying drawings Fig. 1 is an elevation of a rope making machine in connection with which the spreader is used. Fig. 2 is a plan view showing the rope partly made. Fig. 3 is a plan of the spreader 35 removed. Fig. 4 is a section on the line 4—4 of Fig. 3. Fig. 5 is a side elevation of the small spreader or member and Fig. 6 is a section on the line 6—6 of Fig. 5.

In the drawings, 6 indicates the driving 40 mechanism for revolving the strands. This may be of the usual type and forms no part of the present invention. The rope 7, being made, is connected by a swivel hook 8 to a cable 9 passing over a pulley 10 to a 45 weight 11, to give the proper tension on the rope. This apparatus is also old.

The spreader forming the present invention is set in between the strands of which

the rope is formed, as shown in Figs. 1 and 2, each strand being indicated at 10^a. 50 The spreader comprises a larger body or member 12 having the form of a spider or wheel with spokes 13 and a rim 14, and at the end of each spoke, a notch 15 is formed in the rim. This notch is heart-shaped, or 55 provided with overhanging lips 10 at its opposite sides, these lips serving to confine the strands in the notches in which they are engaged. This larger body or member is connected by a tubular rod 17 to the small 60 body or member 18. This has the general form of a circular spider with notches 19 in its rim and overhanging lips 20 at the sides of said notches, with the same effect as above described. These two members are 65 mounted on opposite ends of the tube 17, and the latter being hollow provides an axial passage or guide through which a central cord or wire or other reinforcing member may be fed into the rope; or when 70 the machine is used for making electric cords an insulated wire can be fed through this tube. At all events this tube serves the purpose of permitting a core of any material desired to be fed into the rope at the 75 axis of rotation. The spreader confines and guides the strands as they are revolved to twist the rope, and the difference in diameter guides the strands at an inclination toward the center of rotation, to give the desired pitch to the twist of the rope. The manner of operation of the spreader is 80 quite obvious and will be appreciated by those skilled in the art.

I claim:

A spreader for rope making machines comprising two spiders having spokes and notched rims, and a hollow spacing bar secured at its ends to the hubs of the spiders.

In testimony whereof, I affix my signature in presence of two witnesses.

WILLIAM H. FULLINGTON.

Witnesses:

I. F. BURTON,
BESSIE F. POLLAK.
